UNITED STATES PATENT OFFICE.

GEORGE P. BURKE AND PETER D. BURKE, OF ROSWELL, SOUTH DAKOTA.

SCREENING-MACHINE.

No. 901,512.

Specification of Letters Patent.

Patented Oct. 20, 1908.

Application filed April 2, 1908. Serial No. 422,815.

To all whom it may concern:

Be it known that we, GEORGE P. BURKE and PETER D. BURKE, citizens of the United States, residing at Roswell, in the county of Miner, State of South Dakota, have invented a new and useful Screening-Machine, of which the following is a specification.

This invention relates to a machine designed primarily for screening sand, but it is applicable for separating the fine particles from the coarse of other materials.

One object of the invention is to provide a simple, strong and convenient machine for the purpose stated, the parts of which can be quickly separated or "knocked-down" and the supporting frame folded flat to enable the parts being readily transported from place to place with great ease, a saving of time and economy of space.

Another object of the invention relates to the screening cylinder, the foraminous covering of which may be quickly removed and, if worn out, replaced by a new one, or by one of larger or smaller mesh if so desired with very little loss of time.

A further object of the invention resides in the use of a force feed attachment applied to the cylinder shaft within the hopper and at the mouth of the cylinder to assure the proper feeding of material thereto.

With these and other objects in view the invention consists of the novel construction, combination and arrangement of parts hereinafter described and claimed, reference being had to the accompanying drawing in which—

Figure 1 is a view in side elevation partly in section of the improved screening machine; Fig. 2 a view in elevation of the tail end of the machine; Fig. 3 a longitudinal section of the revolvable screen; Fig. 4 a perspective view of a detail of construction.

Similar reference numerals are used for the same parts in all the figures.

Referring to the drawing, the numeral 1 indicates the folding frame supporting the screening mechanism which, in this instance, comprises the vertical legs 2 at the head of the machine, the similarly disposed legs 3 at the tail end thereof and cross braces 4 extending diagonally between the legs 2 and 3 on each side of the machine. These parts are connected to one another by bolts 5 and 6, the latter bolts, joining the upper ends of the cross braces 4 to the upper ends of the legs 2 and 3 and are removed when the ma-

chine is to be disassembled, the bolts 5 serving as pivotal points on which the elements of the frame are folded.

The legs 2 and 3 converge slightly towards the top, as represented in Fig. 2, the legs 3 being preferably formed of a single piece of material bent to form an arched top 7 on which one of the bearings 8 for the longitudinal screen shaft 9 is bolted. A cross piece 65 extends between the legs 2 near their upper end to serve as a brace and as a support for the upper bearing 8 of shaft 9 which bearing is preferably cast integral with said brace. The bearing 8 on the arch 7 is lower than the one at the other end so that the shaft will incline downwardly towards the tail of the machine.

Mounted on the shaft 9 to revolve therewith is the screening cylinder 10 in communication at its head end with the feeding mechanism 11 and at its tail end with a spout 12 to carry off the material too large to pass through the screening material. The screen 10 is constructed with a head and tail ring 13 and 14, respectively, each connected by curved spokes 15 to a hub 16 fast on the shaft 9. The concave sides of the spokes face the head of the cylinder to facilitate the entrance of material at one end and the exit of refuse at the opposite end. Surrounding the rings 13 and 14 and extending between them is the foraminous screen 17 which may be woven wire, perforated metal or other material suitable for the purpose, but here shown as woven wire. The screening material 17 is securely held in position by a removable frame 18 clamped on the rings 13 and 14 over said material.

The frame 18 is formed of two or more circular bands 19 connected together by a number of narrow parallel slats 20 screwed, riveted or bolted to the bands and equally spaced. The bands are made preferably of spring metal and may be in two parts with 100 projecting lugs 21 oppositely disposed on each part and perforated to receive clamping bolts 22, as in Fig. 3, or of a single piece with fastening lugs on one side only, see Fig. 2. After the screening material has been applied to the rings 13 and 14 and tightly stretched thereon the frame 18, if the bands are in one piece is sprung open and slipped endwise over the screening cylinder 10 until the end bands 19 surround the rings 13 and 14, the bolts 22 are then applied and the bands clamped firmly around said rings.

tightly fastening the screening material in place. If the two part frame 18 be used the parts of the frame are fitted over the cylindrical screen 10 from opposite sides and clamped. Should the distance between the rings 13 and 14 be too great for the screening material to retain its shape when the machine is in operation, one or more bands 19 may be placed between the end bands, and 10 an equal number of supporting rings 23 placed within the screen 10 for the bands to press against.

The legs 2 project above the shaft bearing 8 and are bolted to a hopper 24 into which 15 the material to be screened is thrown. Projecting rearwardly from the bottom of the hopper is a tubular outlet 25 extending a short distance into the screen 10 and concentric with the shaft 9 which passes there- 20 through and through the lower end of the hopper. The head of the screen is closed by a board or plate 26 except for a central opening to admit the tubular hopper outlet 25. By means of the closure 26 the material to be 25 screened is prevented from working out of the head end of the screen.

The quantity of sand or other material admitted to the screen 10 is regulated by a sliding gate 27 movable in guides on the rear 30 wall of the hopper 24 above the entrance to the tubular outlet 25. Raising and lowering the gate changes the size of the outlet and hence the quantity of material passing to the screen.

35 Removably secured on the shaft 9 within the hopper is a force feed attachment 27 comprising a hub with rearwardly projecting fingers 29 thereon. These fingers are preferably set at an angle to the axis of the shaft 40 to force the contents of the hopper into the screen. The force feed attachment when not necessary may be removed from the shaft.

The outlet spout 12 at the tail of the screen 45 10 is removably supported on the frame 1 in any convenient manner as by hooks 30 engaging notches or eyes on one of the cross braces 4 and legs 3. The machine may be operated by a hand crank 31 on the shaft 9, 50 or by power through the pulley 32 on the same shaft.

When the screening machine is to be transported, certain parts thereof are for convenience separated from one another or 55 knocked-down in the following manner. The outlet spout 12 is removed and the bolts 6 disconnected from the upper ends of the cross braces 4 so that the main frame 1 may be extended longitudinally until the bearing 8 on the legs 3 is free of the shaft 9. The crank 31 and the pulley 32 having been removed from the shaft 9 the latter, with the screen 10 and force feed attachment therein 60 is withdrawn from the bearing 8 at the head 65 of the machine. The main frame 1 with the

hopper attached can now be folded on the pivot bolts 5 into a much smaller and more convenient compass by turning the upper ends of the front and rear pair of legs inwardly towards each other as will be understood. The machine is thus reduced to three conveniently handled pieces, the frame, the shaft and its attachments and the tail spout. These parts can be loaded on a small wagon or cart and conveyed with ease 75 from one locality to another, or if shipped in this condition less space is occupied and the machine is handled with greater ease and more quickly than if it were set up.

It is to be noted that the rings which support the screening material and the bands by which said screen is held on the rings may be circular, elliptical, pentagonal or of other shape best suited to the purpose desired; and that where rings and bands are used in the specification and claims such words are to be taken in the broadest sense.

Having described our invention what we claim as new and desire to secure by Letters Patent is:—

1. The combination in a screening machine of a shaft, a cylindrical screen mounted thereon, and a flexibly jointed main frame provided with bearings for said shaft, said frame being longitudinally extensible to permit the removal therefrom of the cylinder and shaft.

2. The combination in a screening machine of a shaft, a cylindrical screen mounted thereon, a longitudinally extensible knock-down frame having bearings for said shaft, the extension of the frame permitting the removal of the shaft and cylinder and detachable means normally holding said frame in shaft-holding position.

3. The combination in a screening machine of a longitudinally extensible frame formed of a plurality of pivotally connected sections, detachable means for locking the parts of the frame rigidly together, bearings on said frame, a shaft mounted in said bearings, a revoluble screen on said shaft and a feed hopper connected to the frame and having an opening for the passage of the shaft.

4. The combination in a screening machine of a shaft, a revoluble screen mounted thereon, a flexibly jointed main frame provided with bearings for said shaft, a hopper supported by the frame and opening into said screen, said hopper having an opening for the passage of the shaft, and cross-braces pivotally connected at their lower ends to said main frame and detachably connected at their upper ends to said frame, whereby on loosening the detachable connections said main frame may be elongated to permit of the removal of shaft and screen.

5. The combination in a screening machine of a shaft, a revoluble screen mounted thereon, a flexibly jointed main frame comprising

a pair of legs at one end provided with a bearing for said shaft and a hopper fixed to said legs, a pair of legs at the opposite end of said frame supporting a second shaft bearing, 5 cross-braces pivotally connected together and to the lower ends of said legs and detachably connected for securing the upper ends of said cross-braces to the upper ends of said legs whereby on the removal of said detachable connections the main frame may be 10 elongated to permit the removal of the shaft

and screen and then folded in an approximately flat form.

In testimony that we claim the foregoing as our own, we have hereto affixed our signatures in the presence of two witnesses.

GEORGE P. BURKE.
PETER D. BURKE.
